UNITED STATES PATENT OFFICE.

WILLIAM NEWGENT, OF WEST BADEN, INDIANA.

RAIL-JOINT.

No. 880,906.

Specification of Letters Patent.

Patented March 3, 1908.

Application filed June 28, 1907. Serial No. 381,262.

To all whom it may concern:

Be it known that I, WILLIAM NEWGENT, a citizen of the United States of America, residing at West Baden, in the county of Orange and State of Indiana, have invented new and useful Improvements in Rail-Joints, of which the following is a specification.

This invention relates to rail joints, and one of the principal objects of the same is to provide a simple, strong, durable and efficient joint for the ends of railway rails which will not require the use of bolts and nuts.

Another object of the invention is to provide a rail joint or splice which will not spread, creep or sink in use, and in which the rolling stock will not pound in passing over the joint, and in which threaded bolts are entirely dispensed with.

These and other objects may be attained by means of the construction illustrated in the accompanying drawing, in which:

Figure 1 is a perspective view of the meeting ends of a pair of railway rails joined in accordance with my invention. Fig. 2 is a perspective view of the male member of the joint. Fig. 3 is a similar view of the female member of the joint. Fig. 4 is a transverse vertical section on the line 4—4, of Fig. 1. Fig. 5 is a similar view on the line 5—5 of Fig. 1.

Referring to the drawing for a more particular description of my invention, the numeral 1 designates what I may term for convenience in this description, the male member of the joint, said male member comprising an ordinary railway rail, one end of which is provided with an integral rail chair 2 which terminates at some distance back of the end of the rail and is provided with a shoulder 3. Near the end of the rail is a reduced portion 4 having oppositely disposed shoulders 5, and at the end of the reduced portion 4 is a neck 6 having oppositely disposed shoulders 7 and projecting from the neck 6 is a dove-tail tenon 8. Projecting from the under side of the neck 6 is a lug 9 provided with a slot 10 and underneath the rail portion some distance back of the lug 9 is a similar lug 11 also provided with a slot 12.

The female member 13 of the joint consists of a chair member 14 formed integral with the end of the rail and projecting be-

yond the shoulders 15 formed at the ends of the parallel members 16. A reduced recess 55 17 is formed in the female member and shoulders 18 are disposed at the opposite sides of said recess, and a dove-tailed mortise 19 is formed at the opposite end of the recess 17 from the shoulders 18. A squared 60 aperture 20 is formed in the floor of the chair 14 and a similar aperture is formed at the bottom of the recess 17. The meeting ends of the rails are united by placing the dove-tailed portion 8 in the mortise 19 with 65 the lug 9 extending through the aperture 10 at the bottom of the recess 17, while the lug 11 extends through an aperture similar to the one designated as 20. Keys or wedges 21 are driven through the slots 10 and 12 in 70 the lugs 9 and 11 to hold the joint firmly connected.

It will be understood that each rail has at one end a male member and at the opposite end a female member, thus making the 75 joints continuous from one end of a track to the other by uniting the parts as has been described.

From the foregoing it will be obvious that a rail joint made in accordance with my invention is exceedingly strong and durable, will prevent the rails from spreading or sinking, and that the rolling stock in passing over the joint will not pound, and that threaded bolts are entirely dispensed with 85 in connecting the rails together.

Certain changes may be made in the details of construction without departing from the spirit and scope of the invention as defined in the claims.

Having thus described the invention, what I claim is:

1. A rail joint comprising a rail having at one end a male member consisting of an integral chair, a reduced portion, a neck 95 and a dove-tailed tenon, slotted lugs extending downwardly from said male member, and a female member conforming to said male member and provided with openings therein for the slotted lugs, and keys 100 driven through the slots in said lugs transversely of the rails.

2. In a rail joint, a male member comprising an integral chair, a reduced portion, shoulders at opposite sides of said reduced 105 portion, a neck, shoulders at opposite sides

of said neck, a dove-tailed projection, slotted lugs extending downwardly from said member, a female member comprising an integral chair, oppositely disposed parallel members, a recess and a dove-tailed mortise, said chair having apertures in the bottom thereof through which the slotted lugs are extended, and wedge shaped keys driven

transversely through the slots for locking the two members together.

In testimony whereof, I affix my signature in presence of two witnesses.

WILLIAM NEWGENT.
